UNITED STATES PATENT OFFICE.

FRED P. OLDS, OF BEREAL, OHIO.

DESIGN FOR A SHOE-LAST.

SPECIFICATION forming part of Design No. 32,520, dated April 10, 1900.

Application filed March 6, 1900. Serial No. 7,602. Term of patent 34 years.

To all whom it may concern:

Be it known that I, FRED P. OLDS, a citizen of the United States, residing at Berea, in the county of Cuyahoga and State of Ohio, have invented and produced a new and original Design for a Shoe-Last; and I do hereby declare the following to be a full, clear, and exact description of the same, reference being had to the accompanying drawing, forming a part thereof.

This invention relates to a new and original design for a shoe-last; and it consists of a shape and configuration as shown in the accompanying drawing and hereinafter described.

In the drawing the last is shown in perspective.

A designates a sole-piece having a marginal bead or flange B, which extends upward from the sole-piece and encompasses the entire edge of the sole. The sole-piece is conveniently thin and substantially flat.

C designates the socket portion, extending upwardly and having one side open. The

base of the socket is shown larger than the upper end.

D is a rib inclined and tapered, the same extending from the toe centrally along the sole-piece backward and terminating at the front wall of the socket member. Its upper edge is curved, as shown, and at the forward end joins and is flush with the upper edge of the flange B.

The essential features of the design are the sole-piece having the marginal flange or bead, the central flange or rib, and the socket.

Having thus described the invention, what is claimed as new, and desired to be secured by Letters Patent, is—

The design for a shoe-last, substantially as shown and described.

In testimony whereof I affix my signature in presence of two witnesses.

FRED P. OLDS.
